Primary Examiner — Karen S Acker*Assistant Examiner* — Steven B Reinhardt, Jr.(74) Attorney, Agent, or Firm — Troutman Sanders, LLP; Christopher C. Close, Jr.(57) CLAIM

We claim the ornamental design of a window box with handles, substantially as shown and described.

DESCRIPTION

FIG. 1 is a front perspective view of a window box with handles in accordance with my new design; FIG. 2 is a left side view of the window box with handles in FIG. 1;

FIG. 3 is a right side view thereof;

FIG. 4 is a front view thereof;

FIG. 5 is a back view thereof;

FIG. 6 is a top view thereof; and,

FIG. 7 is a bottom view thereof.

The broken lines depict portions of the window box with handles that form no part of the claim.
